The ornamental design for an operation panel for a floor scrubber, as shown and described.

DESCRIPTION

FIG. 1 is a front elevational view of a operation panel for a floor scrubber showing our new design;

FIG. 2 is a rear elevational view thereof;

FIG. 3 is a top plan view thereof;

FIG. 4 is a bottom plan view thereof;

FIG. 5 is a left side elevational view thereof;

FIG. 6 is a right side elevational view thereof; and,

FIG. 7 is a reduced perspective view thereof, the broken line showing of a floor scrubber being for illustrative purposes only and forming no part of the claimed design.
